US00D828850S

(12) **United States Design Patent** (10) Patent No.: **US D828,850 S**
Smith et al. (45) Date of Patent: ** *Sep. 18, 2018

(54) **DISPLAY SCREEN OR PORTION THEREOF WITH GRAPHICAL USER INTERFACE**

(71) Applicant: **SNCR, LLC**, Bridgewater, NJ (US)

(72) Inventors: **Andrew J. R. Smith**, Purchase, NY (US); **Daniel Faltyń**, New York, NY (US)

(73) Assignee: **Synchronoss Technologies, Inc.**, Bridgewater, NJ (US)

(*) Notice: This patent is subject to a terminal disclaimer.

(**) Term: **15 Years**

(21) Appl. No.: **29/574,196**

(22) Filed: **Aug. 12, 2016**

CLAIM

The ornamental design for a display screen or portion thereof with graphical user interface, substantially as shown and described.

DESCRIPTION

The FIGURE is a front view of a display screen or portion thereof with graphical user interface showing our new design.

The long broken lines in the FIGURE show a display screen or portions thereof that form no part of the claimed ornamental design. The short broken lines show portions of the graphical user interface that form no part of the claimed ornamental design.
